UNITED STATES PATENT OFFICE.

MARSDEN H. HUNT, OF OAKLAND, CALIFORNIA, ASSIGNOR TO WESTINGHOUSE ELECTRIC & MANUFACTURING COMPANY, A CORPORATION OF PENNSYLVANIA.

MOLD FOR CASTING INSULATORS.

Application filed October 11, 1923. Serial No. 667,881.

To all whom it may concern:

Be it known that I, MARSDEN H. HUNT, a citizen of the United States, and a resident of Oakland, in the county of Alameda and State of California, have invented a new and useful Improvement in Molds for Casting Insulators, of which the following is a specification.

My invention relates to strain insulators of the class known as link strain insulators and more particularly to a mold for making such insulators in a single operation.

The objects of my invention are to provide a mold for such an insulator which shall form the same in a single operation, which shall, at the same time, form passages or openings in the body thereof and shall afford an inexpensive, efficient and convenient means of producing insulators of this class by molding.

Insulators have been cast heretofore, but there has not been found, in the prior art, a means of forming apertures or openings through the body of the insulator during the process of casting the insulator body. To produce such openings it has been found necessary to cut the same through the insulator body by a special cutting tool, while the insulator was in a plastic state and this necessitated a separate handling and operation apart from the casting. There resulted from this cutting considerable loss because of breakage of the insulators. By the use of my mold I am enabled to overcome the difficulties of the prior art and to produce by casting, a much stronger and more uniform insulator, at a less cost and with less handling than heretofore.

My invention consists, substantially, in the provision of a mold, having a base and a plurality of sides co-operating therewith, which are provided with core members of such conformation that when the parts of the mold are assembled and a clay suspension cast therein they will not only form the body portion of the insulator of the desired shape but will, at the same time, form therein the apertures or openings desired. The sides may be readily and separately removed and disassembled from the base and insulator leaving the latter in its required plastic form.

Referring to the accompanying drawings constituting a part hereof and in which like reference characters indicate like parts,

Figure 1 is a horizontal sectional view of my mold, taken along line I—I of Fig. 2;

Fig. 2 is a side elevational view thereof showing one of the sides of the mold removed;

Fig. 3 is a vertical sectional view taken along line III—III of Fig. 2, looking in the direction of the arrows;

Fig. 4 is a sectional view of the base of my mold with the sides and top of the mold removed therefrom showing an insulator supported thereon;

Fig. 5 is an elevational view of one of a pair of complementary sides and core members of my mold; and

Fig. 6 is an elevational view of one of the other pair of complementary sides and core members of my mold.

Referring more particularly to the drawings, the mold consists of a base 1 which, in the form illustrated here, is provided with a central elevated portion 2, which is adapted to position the respective side and top members constituting the body of the mold, on the base 1.

Oppositely positioned on the base 1 is a pair of sides 3 and 4 which carry, preferably, integrally therewith, core members 5 and 6 respectively projecting from their inner faces and meeting approximately over the center line of the base. Two other oppositely positioned sides 7 and 8 are mounted on the base 1 in co-operative relation therewith and with the sides 3 and 4. The sides 7 and 8 are provided with extended top portions 9 and 10, respectively, which meet approximately over the central axis of the base 1 and provide a top for my mold.

The side members 7 and 8 are provided with core members 11 and 12, respectively, preferably integral therewith, which extend from the inner faces of said sides and meet approximately at the vertical central axis of the base, similarly to the core members 5 and 6 but in a different horizontal plane; and at right angles thereto. The top formed by members 9 and 10 is, at the central portion thereof, provided with an aperture 13 through which the plastic material, such as clay in suspension of which my insulator may be made, may be poured or otherwise introduced into the body of the mold.

The base 1 is provided with a dished-out or insert portion 14 near the center of its upper surface and there is further provided in

this dished-out portion, insets or recesses 15 and 16 adapted to form feet or lugs upon one face of the insulator. The top portions 9 and 10 of the sides 7 and 8 are likewise, near the extremities that meet over the central portion of the mold, dished out or recessed so as to give the desired formation to the opposite face of the insulator when cast.

My mold is preferably made of plaster 10 Paris, but any substance having the desired porosity, tensile strength and absorptive power may be substituted therefor.

In casting an insulator with my improved mold the sides are co-operatively assembled upon the base 1, so that sides of similar or desired conformation shall be properly placed, in this case oppositely. They are then securely bound together by any suitable holding means, so that they will not move or accidentally become disassembled during the casting operation.

A plastic or semi-liquid substance, preferably clay or a clay-like body in suspension in water, of a constituency such that the mass will weigh approximately 59 ounces per quart, may be then poured or otherwise introduced into the mold, through the opening 13, until the mold is substantially filled. The mold is then allowed to stand for a short period, sufficient to permit the water of the solution to be absorbed by the body of the mold and to effect the resultant semi-drying and depositing of the suspended material within the mold. More material is introduced into the mold and is permitted to deposit its suspended material within the mold. This is repeated successively until the mold is completely filled with the deposited substance and the insulator is then and thereby formed.

The sides and top of the mold, being separately removable from the base, are then withdrawn from the molded insulator and the same is in the form shown in Fig. 4, resting upon the base of the mold with the surface contour and openings therein complete. The insulator is then removed from the base and is air-dried at a temperature increasing from normal to about 100° C. This drying is continued for several days. The insulator is then glazed by dipping in a glazing solution and is fired at a high temperature for approximately three days, the firing temperature rising to approximately 2450° Fahrenheit. The insulator is then gradually cooled in the kiln for approximately three days. The firing of the insulator progresses in such manner that the rise of temperature to 2450° Fahrenheit is much more sudden than the decrease of temperature to normal during the cooling process. After the cooling process the insulator is ready for use.

The recesses or insets 15 and 16 (Fig. 4) 85 form feet on one side of the insulator upon

which it is found desirable to permit it to stand or rest during the drying, firing and cooling steps of the process of manufacture.

It will be seen from the foregoing that I have provided a mold for insulators of this character which is very convenient and efficient in operation, may be easily assembled and disassembled, which is of inexpensive durable and simple construction and by which I am enabled to form an insulator having openings therein by a minimum number of operations without drilling or cutting. My improved mold will so form insulators of this type that internal strains resulting from their drying will not produce surface or internal cracks therein and it may have other advantages and results not herein specifically set forth, but which may be obvious from the drawings and the accompanying specification.

Although I have particularly described and claimed the invention herein, I do not wish to be unnecessarily limited thereby, except as the state of the art and the appended claims may require, for it is obvious that various changes and modifications may be made therein without departing from the spirit and scope of my invention.

For instance, in the insulator here illustrated, it has been necessary to make cores, on the opposite sides of the mold, somewhat oblique, truncated, substantially coniform, tapering or bell-like in shape so that the insulator will be given the desired surface contour. It will, however be understood that, although I have illustrated this shape of core to correspond with this shape of insulator, yet my mold may be provided with core members which will vary according as the shape or contour of the insulator desired to be molded is varied.

I claim as my invention:

1. A mold for forming insulators of the link type comprising a structure having core portions disposed in crossed spaced relation to form the interlinked openings thereof and constructed for withdrawal from the insulators that are molded therein.

2. A mold for forming insulators of the link type comprising a structure having core portions disposed in crossed spaced relation to form the interlinked openings thereof, said structure also being constructed to provide resting-base portions on the insulators and to permit the withdrawal of the structure from the insulators that are molded therein.

3. A mold for forming insulators of the link type comprising a structure having portions conforming to the ends of the insulators and core portions disposed in crossed spaced relation to each other and in spaced relation to said end portions to form the interlinked openings of the insulators.

4. A mold for forming insulators of the

link type comprising a plurality of separable members having core portions disposed in crossed spaced relation and shaped to form the interlinked openings of the insulators.

5. A mold for forming insulators of the link type comprising a pair of oppositely-disposed members each having a core-portion projecting toward the core-portion of 10 the other to form a portion of one opening of the insulator, and a second pair of similarly disposed members each having a core-portion projecting toward the core-portion of the other in spaced substantially right- 15 angular relation to the core portions of said first pair of members to form a portion of the other opening of the insulator.

6. A mold for forming an insulator of the link type comprising a pair of oppositely-disposed members each having a projecting core portion co-operating with the core portion of the other to form a substantially solid bridge between the members conforming to one opening of the insulator and 25 a similarly shaped and related pair of members co-operating with said first pair to form the other opening of the insulator.

7. A mold for forming an insulator of the link type comprising a structure including an end portion having a portion conforming to one end portion of the insulator, a pair of members each having a projecting core portion co-operating with the core portion of the other to form one opening of the 35 insulator, a pair of members similarly provided with core portions in crossed spaced relation to the core portions of the first pair to form the other opening of the insulator, and an end portion having a portion conforming to a portion of the other end of the 40 insulator.

8. A mold for forming an insulator of the link type comprising a structure including an end portion having a portion conforming to one end portion of the insulator, a pair of members each having a projecting core portion co-operating with the core portion of the other to form one opening of the insulator, a pair of members similarly 45 provided with core portions in crossed spaced relation to the core portions of the first pair to form the other opening of the insulator, and an end portion having a portion conforming to a portion of the other end of the 50 insulator, one of said end portions

of the mold structure being also formed to provide a resting support portion on the insulator.

9. A mold for forming an insulator of the link type comprising a base member 60 having a portion conforming to one end portion of the insulator, a pair of members each having a projecting core portion co-operating with the core portion of the other to form one opening of the insulator, and a 65 pair of members similarly provided with core portions in crossed spaced relation to the core portions of the first pair to form the other opening of the insulator, said second pair of members each also having a portion co-operating with the other to form a portion of the other end of the insulator.

10. A mold for forming an insulator of the link type comprising a base member having a portion conforming to one end portion 75 of the insulator, a pair of members fitted to said base member and each having a projecting core portion co-operating with the core portion of the other to form one opening of the insulator, and a second pair of 80 members similarly fitted to the base member and provided with core portions in crossed spaced relation to the core portion of the first pair to form the other opening of the insulator, said second pair of members each 85 also having a portion co-operating with the other to form a portion of the other end of the insulator.

11. A mold for forming an insulator of the link type comprising a base block having 90 a raised top portion providing a perimetral shoulder and conforming to one end of the insulator, a pair of oppositely-disposed side members having shoulders for co-operation with the shoulders of the block 95 and co-operating core portions for forming an upper opening in the insulator, and a second pair of oppositely-disposed side members having shoulders for co-operation with the shoulders of the block and co-operating 100 core portions in spaced crossed relation to said first core portions for forming a lower opening in the insulator, said latter side members also having co-operating top portions conforming to the other end of the insulator.

In testimony whereof, I have hereunto subscribed my name this 22nd day of September, 1923.

MARSDEN H. HUNT.
